UNITED STATES PATENT OFFICE.

JOHN WHITAKER, OF NORTH WALES, PENNSYLVANIA.

DESIGN FOR A FRAME FOR A CHECK-WRITING MACHINE.

50,437.

Specification for Design.

Patented Mar. 6, 1917.

Application filed November 29, 1916. Serial No. 134,214. Term of patent 14 years.

To all whom it may concern:

Be it known that I, JOHN WHITAKER, a citizen of the United States, and a resident of North Wales, county of Montgomery, State of Pennsylvania, have invented a certain new, original, and ornamental Design for the Frame of a Check-Writing Machine, of which the following is a specification, reference being had to the accompanying drawing, forming part thereof, in which—

Figure 1 is a plan view of the frame of a check writing machine forming the subject of my new, original and ornamental design; and

Fig. 2 is a perspective view thereof.

I claim:—

The ornamental design for a frame of a check writing machine, substantially as shown.

JOHN WHITAKER.
